METAL ARTICULATED SHOE LAST

George C. Clark, Beverly Hills, Calif.

Application February 3, 1934, Serial No. 709,584

13 Claims. (Cl. 12—136)

The invention relates to metal articulated shoe lasts, and particularly to articulated shoe lasts comprising hollow toe and heel members, pivotally interconnected and formed of a metal, such as 5 aluminum.

Articulated shoe lasts have heretofore been largely made of wood, by reason of the difficulty and expense attendant upon attempts to manufacture the lasts of other material and particularly of metal. Articulated shoe lasts must be made in a manner whereby the hinged sections thereof fit precisely to provide the exact desired contour of the last as a whole. A further requirement is that, for minimum cost and facility of handling, a last, if made of metal, must be hollow, which thus limits methods of manufacture to casting or molding thereof. The casting of the last sections or parts, however, requires finishing and polishing thereof if the casting mold is formed of sand, and it will be seen that a rough casting affords no finished portion with respect to which the remainder of the finishing operation can be carried on with assurance that each of the units cast will be of the exact form necessary. In this respect, it will be obvious that, unless means is provided for exactly positioning a rough casting with respect to the finishing means, the expense and difficulty of making which means, as a jig, is great, and the use of which requires pains-taking care in the adjustment of each individual casting, a slight variation of position with respect to the finishing means will throw the entire last out of balance or out of shape, whereby that last section or member will not properly fit the complementary last member and will not, in combination with the other last member, produce the desired last contour. Another method of casting the last sections would be to cast them in a metal mold, but this entails great and impractical expense by reason of the large number of sizes of the lasts, and also by reason of the great variation in shapes of lasts required by shoe manufacturers to permit manufacture of shoes of different styles and shapes, even though the same size. Necessarily each different last size, and each different shape for each size, requires an individual metal mold for the casting of each of the two parts thereof. These and other difficulties have prevented commercial development of an articulated shoe last for the manufacture of leather shoes, which is formed of metal.

It is therefore the primary object of the invention to provide an articulated hollow metal shoe last which may be simply and cheaply manufactured.

A further object is to provide an articulated hollow metal shoe last whose hingedly connected sections are provided with joint faces which are cast against a chill, whereby said faces will be finished when cast to provide a point from which the balance of the finishing work to be done may be carried, and whereby said faces, to which the friction and wear incident to use of the last is applied, are hardened.

A further object is to provide a hollow metal, 10 articulated shoe last having novel means for hingedly connecting the toe and heel sections thereof.

A further object is to provide an articulated shoe last with novel means for urging the pivotally 15 connected last sections to either of their extremes of pivotal movement.

With the above and other objects in view, the invention resides in the combination and arrangement of parts as hereinafter set forth, shown 20 in the drawing, described and claimed, it being understood that changes in the precise embodiment of the invention may be made within the scope of what is claimed without departing from the spirit of the invention.

In the drawing:

Figure 1 is a view of the last in side elevation.

Figure 2 is a vertical longitudinal sectional view of the last taken on line 2—2 of Figure 3.

Figure 3 is a fragmentary perspective view of 30 the toe member of the last illustrating the construction of the joint face thereof.

Figure 4 is a fragmentary perspective view of 35 the heel member of the last illustrating the construction of the joint face thereof.

Figure 5 is a fragmentary sectional view similar to Figure 2, illustrating the joint parts at their opposite extreme of pivotal movement.

Referring to the drawing, which illustrates the preferred embodiment of the invention, the numeral 10 designates the last, which is preferably formed of cast hollow metal, such as aluminum, as a whole. The last is formed of a toe member 11 and a heel member 12, which members are pivotally or hingedly connected by a pintle 13. 40 Heel member 12 is provided with a joint face 14, a part of which comprises the faces of the integrally formed knuckles 15 formed at the opposite sides of the member and spaced at their inner ends, and between which and in alignment with which is formed a concave face 16 concentric with said knuckles. Aligned apertures 17 are formed centrally in the knuckles 15 for the reception of the pintle 13. The portions of the joint face above and below the knuckles are relatively 45 50 55

angularly disposed, as best shown in Figure 2. Toe member 11 is provided with a joint face 18, a part of which comprises the concave portions or recesses 19, which are adapted to receive the 5 knuckles 15 of the heel member, and the faces of an intermediate knuckle 20 concentric of and aligned with said concavities 19, which knuckle 20 is adapted to fit into the concavity 16 of the heel member. Knuckle 20 has a sleeve 21, preferably formed of steel or other hard metal, mounted centrally therein to form a bearing for the 10 pintle 13. The joint faces of the last parts, being the surfaces to which frictional wear is applied, must be hardened, particularly when the last is 15 made of a comparatively soft metal, such as aluminum, and for this reason and also to facilitate manufacture in the respects set forth above, these joint faces are formed by being cast against a chill. The difficult operation of machining 20 these faces is thus eliminated, and insurance that the last members will precisely and exactly fit together to provide the desired contour of the last is obtained.

Integrally formed with the heel member 12 in 25 the casting operation is a pocket 25 whose mouth opens in the concave face 16 and the axis of whose bore extends radially of the center of the knuckles 15 and substantially parallel with the top face 26 of the heel member. In this bore 25 is disposed a strong coil spring 27 which outwardly urges a metal ball 28 into engagement with the knuckle 20 of the toe member. An opening 29 is formed in the knuckle 20 of the toe member, the axis of which extends radially of said 30 knuckle and at an angle to the bore of the pocket 25 of the heel member. In this opening 29 is mounted a second metal ball 30 in a manner whereby only a small portion thereof projects beyond the adjacent face of the knuckle. In practice, the ball 30 has a frictional fit with the opening 29 which is provided by forming the opening 29 of a radius a few thousandths of an inch less than the radius of the ball, and then driving said ball, which is much harder than the aluminum, 40 into this opening to displace the metal around said opening to enlarge the opening and at the same time insure a very solid fit of the ball in the pocket. Ball 28 is normally disposed to one side of, i. e. below or above, ball 30, as illustrated 45 in Figure 2, and upon pivoting of the last members relative to each other, ball 28 rolls over ball 30 and is thereby shifted in pocket 25 against the action of spring 27, the construction thus providing a cam action whereby the two balls and 50 the spring serve to prevent pivoting of the last members to any position except the extremes of their movement in either direction. The balls 28 and 30, which take up the greatest portion of the strain and wear involved in the operation of 55 pivoting the last members, are formed of hard metal, as steel, to minimize wear thereof.

The last, while made of comparatively soft metal, is thus provided, by the casting of the joint faces thereof against a chill, with hardened 60 surfaces at the points at which friction and wear occur, in addition to the advantages of manufacture and precision shaping of joint and last contour which result from the use of a chill. The hard metal sleeve 21 permits a knuckle to be used 65 on the toe as well as the heel member to form a joint, the sleeve withstanding the friction and pressure resulting from pivoting of the last parts, which would not be successfully withstood by the aluminum knuckle without the use of such sleeve. 70 The particular cam joint effected by the balls and 75

spring is simple to manufacture, effective for its purpose, and also takes up wear at points where the aluminum would not withstand such wear.

The invention having been set forth, what is claimed as new and useful is:

1. An aluminum shoe last comprising a toe member, and heel member, means for pivotally interconnecting said members including a knuckle formed integrally with one of said members, a hard metal sleeve carried by said knuckle, 10 a pin carried by the other member and journaled in said sleeve, a spring pressed hard metal ball carried by said last named member, and a hard metal ball partially imbedded in said knuckle, said last named ball being positioned centrally of 15 the path of movement of said spring pressed ball.

2. An aluminum shoe last comprising a toe member, a heel member, a pin extending through said members for pivotally interconnecting said members, one of said members having a knuckle 20 formed integrally therewith, a spring pressed hard metal ball carried by the other member, said knuckle having an opening formed therein, and a hard metal ball fixedly lodged in said opening to partially project therefrom, said spring pressed 25 ball passing over said knuckle-carried ball in the pivoting of said last members.

3. A cast aluminum shoe last comprising a toe member, a heel member, means for pivotally interconnecting said members including a knuckle 30 formed integrally with one of said members, a cam projection carried by said knuckle, and spring pressed means carried by the other member and cooperating with said cam, said members having chill cast cooperating surfaces including chill cast 35 knuckle surfaces providing finished slightly hardened joint faces therefor.

4. An aluminum shoe last comprising a toe member, a heel member, means for pivotally interconnecting said members including a knuckle 40 formed integrally with one of said members, the other member having a recess therein of a shape and size substantially complementary to and receiving said knuckle, a pin extending through said last named member and through said knuckle, 45 said last named member having a pocket formed therein, and a spring pressed ball disposed in said pocket to frictionally bear on said knuckle.

5. A shoe last comprising a toe member, a heel member, means for pivotally interconnecting said 50 member including a knuckle carried by one of said members, said knuckle having an opening formed therein, a member fixedly lodged in said opening and having a rounded portion partially projecting from said knuckle, and a spring 55 pressed member carried by the other last member and normally bearing against said last named member and passing over the same in the pivoting of said last members.

6. A shoe last comprising a toe member, a heel 60 member, means for pivotally interconnecting said members including a knuckle integral with one member, the other member having a recess formed therein of a size and shape substantially conforming to said knuckle for receiving the 65 same, said knuckle having a protuberance formed thereon, and spring pressed means carried by the recessed member and passing over said protuberance in the pivoting of said toe and heel members.

7. An aluminum shoe last comprising a heel member having a joint face provided with a central recess, a pair of spaced knuckles formed integrally with said member and aligned with said recess, a toe member having a joint face 75

provided with recesses for the reception of said heel member knuckles, a knuckle formed integrally with said toe member and aligned with said recesses, said last named knuckle having a sleeve formed of hard metal extending therethrough, and a pin carried by the knuckles of said heel member and journaled in said sleeve.

8. A shoe last comprising a toe member and a heel member, one of said members having a joint face provided with a transverse recess, a knuckle formed integrally with said member and projecting therefrom intermediate the ends of said recess, the other member having a joint face provided with a recess for the reception of the knuckle of said first member, a pair of knuckles formed integrally with said last named member on opposite sides of said recess and disposed in the recess of said first member, and a pin pivotally interconnecting said knuckles and recesses of said members being of substantially complementary shape and size to closely interfit.

9. A cast aluminum shoe last comprising a toe member and a heel member, one of said members having a chill cast hardened surface including a transverse recess, a knuckle having chill cast hardened surfaces formed integrally with said member and projecting therefrom in axial alignment with and intermediate the ends of said recess, the other member having a chill cast hardened surface including a recess for the reception of the knuckle of said first member, a pair of knuckles having chilled cast hardened surfaces formed integrally with said last named member on opposite sides of said recess and means for pivotally interconnecting said members with said hard surfaced knuckles and recesses in interfitting relation.

10. A shoe last comprising a toe member, a heel member, said members being formed of an aluminum alloy, and means for pivotally interconnecting said members including a knuckle formed integrally with one member, a harder metal sleeve fixed in said knuckle by the shrinkage of the metal of said knuckle thereon, and a pin carried by the other member and journaled in said sleeve.

5

11. A cast aluminum shoe last comprising a toe member and a heel member, each of said members having a chill cast portion providing a finished hardened joint face including at least one axially aligned knuckle and recess and a surface defining the adjacent ends of said knuckle and recess, and means for pivotally interconnecting said members with said hardened joint surfaces in cooperating interfitting relation.

10

12. A cast aluminum shoe last comprising a hollow toe member and a hollow heel member, each of said members having a chill cast portion providing a finished hardened joint face including concave and convex surfaces, the remaining portions of said members having machine finished surfaces, and means for pivotally interconnecting said members with said hardened joint surfaces in cooperating interfitting relation.

15

13. A cast aluminum shoe last comprising a hollow toe member, a hollow heel member, said members having cooperating curved joint forming portions adapted to interfit, said members having cooperating chill cast hardened surfaces forming joint faces including the faces of said curved joint forming portions, and means for pivotally interconnecting said members.
